UNITED STATES PATENT OFFICE.

ARNOLD KLARWASSER, OF COLOGNE, GERMANY, ASSIGNOR TO CLIMAX-WERKE A. G.
AM ESKENBERG, OF AACHEN, PRUSSIA, GERMANY.

PIPE-BENDING MACHINE.

Application filed June 24, 1925, Serial No. 39,346, and in Germany June 26, 1924.

This invention relates to a machine for manufacturing pipe-bends of the kind comprising a stationary form, a revoluble pipe-bending member and a supporting mandrel 5 movable in the work in conformity with the working movement.

In the methods and machines of the kind known hitherto, the supporting mandrel follows accurately the movement of the revolving pipe-bending member. The cylindrical portion of the mandrel always extends for a certain distance rearwardly beyond the point of contact between the pipe-bending member and the pipe. This is necessary in order to 15 render the mandrel effective and prevent the same from becoming worn out rapidly which would be the case if the mandrel would act on the inner surface of the pipe-wall only along a circular line. The portion of the 20 mandrel referred to is indicated in the drawing by shading. As the supporting mandrel thus has to act on the pipe-wall by a relatively long cylindrical surface, a jamming action is always produced between the mandrel and the pipe-wall. This jamming is 25 without any permanent influence at the beginning and in the course of the bending operation, but it entails an outward bulging of the pipe as soon as the bending member and 30 the supporting mandrel come to a standstill at the end of the bending operation.

The invention has for its object to obviate the said disadvantage, this object being attained by providing the machine with means 35 for imparting to the mandrel a lead with respect to the pipe-bending member shortly before the bending of the pipe is terminated so that the bending of the last portion of the 40 bend takes place without the action of the supporting mandrel.

In the new machine it is possible to define the lead of the mandrel with relation to the revoluble pipe-bending member in such a manner that also in the last part of the bending 45 operation there is neither produced an outward nor an inward bulging. The bend will therefore have a smooth curvature throughout.

Another object of the invention resides in 50 providing means for returning the supporting mandrel always exactly into its initial position in spite of the lead imparted to it in the last part of the bending operation.

The advantages of the present machine re- 55 side in the possibility of relieving the man-

drel of the bending pressure at the end of the bending operation and returning it automatically into its initial position as well as in the great accuracy of adjustment obtainable without any special expenditure of work 60 and time and entirely independent from the skill of the workman.

An embodiment of the subject-matter of the invention is illustrated in the accompanying drawing in which:

Fig. 1 is a plan view, partly in section, of the pipe-bending machine at the beginning of the bending operation, and

Fig. 2 is a similar view of the machine after the bending operation has been termi- 70 nated.

The machine essentially consists of a stationary form *b* and of a pipe-bending member *c* which is adjustably fastened on a frame *d*. The form *b* is of a circular shape and the frame *d* with the member *c* is adapted to revolve around the axis of the form *b*. The frame *d* rests on a stationary base plate *e* which has an annular guiding groove *f* in which a stop *g* is adjustably fastened. The frame *d* has a yoke-like extension *h* provided with a bore *h'* in which is guided a rod *i* which is connected with a bent arm *k*. The rod *i* and arm *k* are connected at *m* with the supporting mandrel *l*. A tension spring *n* is connected by one end to the frame *d* and by its other end to a nose *v* of the arm *k*. The latter has a guiding slot *p* which is engaged by a guide pin *p'* fastened to the frame *d*. Mounted for rotation on the frame *d* is a double-armed lever *q* having arms of different lengths. The movement of the long arm of the lever *q* is limited on the one hand by the arm *k* and on the other hand by a stop *r* on the frame *d*, while its short bent arm terminates in front of a nose *s* of the frame *d*. Screwed on the rod *i* are nuts *t* which serve to adjust the rod *i* with relation to the frame *d*.

The view according to Fig. 2 shows the supporting end of the mandrel *l* in the position in which it is relieved of the bending pressure. Shortly before the bending operation is terminated, the supporting mandrel occupies the position indicated by dotted lines, while the short arm of the lever *q* takes a position against the stop *g*. The further rotary movement of the frame *d* causes a rotation of the lever *q* in such a manner that its long arm moves the rods 100 105 110

k, m, i and the mandrel *l* with relation to the frame *d* and the pipe-bending member *o*, contrary to the action of the spring *n*. Owing to this movement the mandrel has im-
5 parted to it a lead with respect to the mem-
ber *c* shortly before the bending operation is
terminated, so that the supporting end of the
mandrel is already in the straight section of
the pipe *a* and thus relieved of the bending
10 pressure while the last part of the bending
operation is still being executed. As the
bending of the last portion of the pipe-bend
is, in this way, effected without the action of
the mandrel which has been drawn out of the
15 range of the bending pressure, a visible bulg-
ing which otherwise occurs in the bending
of thin-walled pipes, is positively avoided.

After loosening the holder *w* the pipe *a* can
be easily withdrawn from the machine and
20 the frame *d* can be returned into its initial
position (Fig. 1). At the same time, the
rods *k, m, i* and the mandrel *l* are returned
into their initial position by the action of
the spring *n* which contracts until the nuts
25 *t* rest again on the yoke *h* and the lever *q*
carried along by the arm *k* again bears
against the stop *r*.

It will be understood that in bending a
30 pipe, the inner wall, i. e. the wall which
bears against the stationary form *b*, is
jumped while the outer wall, i. e. the wall
acted upon by the bending member *c*, is
drawn or elongated. If no supporting man-
35 drel is used in the interior of the pipe, the
said elongating action will, of course, pro-
duce to a certain extent an inward bulging
of the outer pipe wall. The mandrel there-
fore serves to compensate this inward bulg-
ing by producing an outward bulging. The
40 outward bulging caused by the mandrel is
positive and somewhat stronger than the in-
ward bulging due to the elongation. The
outward bulging therefore outweighs the in-
ward bulging. According to the size of the
45 pipes, this outward bulging ranges between
fractions of a millimeter in small tubes and
about 2 millimeters in large tubes. This
slight outward bulging is of no importance
in the curved portion (bend) of the pipe
50 because it is uniform throughout the bend,
but it would leave a visible disturbant pro-
tuberance or outward bulging at the point
where the curved portion of the pipe passes
into the straight portion, if the mandrel
55 would be allowed to remain in action during
the very last step of the bending operation.
In order to avoid this visible disturbant out-
ward bulging at the end of the bent por-
tion, the mandrel is automatically drawn
60 out of the range of the bending pressure
during the last part of the bending opera-
tion. The result thereof is that in this last
part of the bending operation without man-
drel the elongation of the outer pipe wall
65 compensates the outward bulging and pro-

duces a gradual and smooth transition from
the curved portion to the straight portion
of the pipe.

It will be clear from the foregoing that
the lead is imparted to the mandrel at the
7 end of the bending operation for preventing
the formation of a visible disturbant out-
ward bulging or protuberance at the end of
the bend and for allowing the continued
7 bending operation to produce a smooth trans-
ition from the curved or bent portion to
the straight portion.

Having thus described my invention, what
I claim as new and desire to secure by Let-
ters-Patent, is:—

1. In a pipe-bending machine, comprising
in combination a stationary form, a revolu-
ble pipe-bending member and a support-
ing mandrel movable in the work in con-
formity with the working movement, an au-
tomatically operating stop mechanism for
imparting to the supporting mandrel a lead
shortly before the bending operation is
terminated.

2. In a pipe-bending machine, comprising
in combination, a base plate, a stationary
form, a frame mounted for rotation around
the axis of the form on the base plate, a
pipe bending member carried by and mov-
able with the said frame and a supporting
mandrel likewise carried by the said frame
and movable with relation to the latter and
in the work during the bending operation, a
stop member adjustably fixed on the base
plate, a double-armed lever mounted for
swinging motion on the frame, one arm of
this lever being held in contact with the
mandrel and the other arm of the lever be-
ing adapted to strike against the said stop
member of the base plate shortly before the
rotary movement of the frame and bending
member is terminated and to be rocked by
the said stop member so as to cause the first-
said arm of the lever to impart to the man-
drel a lead with relation to the pipe-bend-
ing member, and stops on the frame for lim-
iting the swinging movement of the lever.

3. In a pipe-bending machine, comprising
in combination, a base plate, a stationary
form, a frame mounted for rotation around
the axis of the form on the base plate, a
pipe-bending member carried by and mov-
able with the said frame and a supporting
mandrel likewise carried by the said frame
and movable with relation to the latter and
in the work during the bending operation,
a stop member adjustably fixed on the base
plate, a double-armed lever mounted for
swinging motion on the frame, one arm of
this lever being held in contact with the
mandrel and the other arm of the lever be-
ing adapted to strike against the said stop
member of the base plate shortly before the
rotary movement of the frame and bending

member is terminated and to be rocked by the said stop member so as to cause the first-said arm of the lever to impart to the mandrel a lead with relation to the pipe-bending member, a spring attached by one end to the mandrel and by the other end to the frame and adapted to return the mandrel and the double-armed lever into their initial positions when the pipe-bending member is returned into its initial position, ¹⁰ stops for limiting the swinging movement of the lever and stops for limiting the movement of the mandrel with relation to the frame.

In testimony whereof I have signed my ¹⁵ name to this specification.

ARNOLD KLARWASSER.
